T. Morrison.

Chronometer Escapement.

No 21,865.

Patented Oct 19, 1858.

Fig. 1

UNITED STATES PATENT OFFICE.

THOS. MORISON, OF NEW YORK, N. Y., ASSIGNOR TO A. S. SOLOMONS, OF SAME PLACE.

CHRONOMETER-ESCAPEMENT.

Specification of Letters Patent No. 21,865, dated October 19, 1858.

To all whom it may concern:

Be it known that I, THOMAS MORISON, of the city of New York, in the State of New York, have invented a new and useful Improvement in Chronometer - Escapements; and I do hereby declare that the following is a full, clear, and exact description thereof, reference being had to the accompanying drawing, through letters of reference marked thereon, forming part of this specification, in which—

Figure 1, represents an elevation of my chronometer escapement. Fig. 2, is an inverted plan of the same, the interior of the cylinder being shown in dotted lines.

The same letters of reference, in both figures, indicate the same parts.

My invention relates more particularly to that class of chronometers which measure time by units, *i. e.* a single beat to each vibration of the balance wheel, and to which class alone, the term "chronometer," in its common acceptation, is now understood to apply; in which as at present constructed the 25 detent is moved in one direction mechanically against the resistance of a spring, and is caused to resume its normal position by the reaction of said spring; the objections to which are—

30 First. That considerable force is required to overcome the power of the spring carrying the detent-pallet, in disengaging it from the tooth of the escapement wheel; to effect this force, it is necessary to use a heavy balance wheel, to overcome the resistance.

35 Second. That the power of the detent spring is liable to be varied considerably, by the slightest change in its position, or by a slight bend or set being given it by a sudden 40 jerk or concussion, which must necessarily impair its operation, or, supposing that no positive injury were done to the spring-detent, by such concussion, it almost invariably checks the vibration of the balance 45 wheel to such an extent as to render its impulse insufficient to disengage the detent against the resistance of the spring; its action consequently ceases; this is extremely liable to be the case with pocket chronometers, from the fact of their being liable to so many sudden motions of the body.

50 Third. That the spring detent and feather spring are necessarily of such extremely delicate proportions and exquisite finish, as 55 to render them too expensive ever to come into common use.

All these objections are overcome in my escapement, in the following manner: First. The detent lever is perfectly balanced, and is moved back and forth mechanically so as 60 to be (as nearly as possible) free from all friction, and unimpeded by the resistance of the detent spring. Second. There being no spring the resistance of which is to be overcome, the heavy balance wheel is unnecessary, and the friction, wear and risk of breakage of its pivots is materially reduced. Third. All the expensive parts of the common chronometer escapement are superseded by others of simpler construction and 70 greater durability, and at a cost scarcely exceeding if equal to that of the escapement of the well known lever watch.

To enable others to make and use my invention, I will now describe its construction 75 and operation, and as it is applicable to every variety of watch, it is deemed superfluous to give any description of the plates, spring, train of wheels, or other parts, common to all watches, and well known.

(a) represents the balance wheel, and (b) the hair spring on an axle (c), which is supported in brackets (d, d'), above and below the upper plate (e), in the usual manner; on this axle is a hollow cylinder (f) 80 with a collar or enlarged cylinder (i i') at each end; one side of the cylinder (f) is open to an extent of about one sixth of its circumference more or less; within said cylinder is a pawl (n) on a pivot, the extreme 85 end of which protrudes a short distance through the aperture in the periphery of the cylinder, and is held to one side thereof, in the position shown in the drawing, by a semi-circular hair spring (r) hooked onto 90 its rear end, and keyed fast to a stud (s) in the opposite side of the cylinder; (g) is the common escapement wheel, (m) is the detent lever, with a detent pallet (u) attached to one side of it, and a curved lateral arm (v) to the other side near its end; all of 95 which are so arranged vertically as that the end of the lever (m) nearly touches the cylinder (f). The arm (v) is on a plane with the upper collar (i), and the detent 100 (u) and escapement wheel (g) are on a plane with the lower collar (i'); at the back of the lever (m) near its outer end is a stud (h) which prevents it from vibrating to that side, while the end of the arm (v) coming in contact with the periphery of the roller (i) 105 prevents its vibration in the other direction,

until, by the oscillation of the cylinder (f), the pawl (n) is brought in contact with the end of the lever (m), at which time a notch in the periphery of the collar (i) comes under the curved end of the arm (v) which allows it to vibrate, by the force of the pawl (n) against it, sufficiently to allow their points to pass each other, at which moment the end of the arm (v) rides the inclined side 10 of the notch, into which it was depressed, onto the periphery of the collar (i) as before; this motion liberates the tooth of the escapement wheel from the detent (u), when the second tooth from it is suddenly 15 brought by the impulse of the main spring against the impulse pallet (o) in the lower collar (i'), which gives impulse to the balance wheel, to be brought back by the hair spring (b); at the moment the tooth of the 20 escapement wheel has passed the pallet (o), another tooth is caught by the detent, to be held until a repetition of the same motion of the cylinder liberates it as before described; in the return motion of the balance 25 wheel the pawl (n) comes in contact with

the back of the lever (m), and having no support, is depressed within the periphery of the cylinder (f) to allow it to pass, and is thrown out again by the spring (v) into its original position, to perform a repetition 30 of its functions as before described.

Having thus described my invention what I claim as new and desire to secure by Letters Patent is—

1. Vibrating the detent of a chronometer 35 (or single beat) escapement, by direct mechanical action substantially as described.

2. I claim the detent lever vibrating on pivots or a staff, when operating in the manner set forth.

3. I claim the arrangement and operation of the pallet (n) in the manner and for the purposes specified.

In testimony whereof, I hereunto subscribe my name this twelfth day of August 45 A. D. 1858.

THOMAS MORISON.
